UNITED STATES PATENT OFFICE.

BOYD ABERNATHY, OF MURPHY, NORTH CAROLINA, ASSIGNOR OF ONE-HALF TO A. A. FAIN, OF MURPHY, NORTH CAROLINA.

AUTOMATIC LIQUID-DISPENSING MACHINE.

1,229,852.

Specification of Letters Patent. Patented June 12, 1917.

Application filed April 3, 1916, Serial No. 88,617.

To all whom it may concern:

Be it known that BOYD ABERNATHY, a citizen of the United States, residing at Murphy; in the county of Cherokee and State of North Carolina, have invented new and useful Improvements in Automatic Liquid-Dispensing Machines, of which the following is a specification.

This invention relates to improvements in automatic liquid dispensing machines and has particular application to an automatic machine for dispensing soda water.

In carrying out the present invention, it is my purpose to provide a machine of the class described whereby, upon the application of a coin of the proper denomination to the machine, the machine may be set in operation to deliver a particular flavor of syrup and a charge of carbonated water in the proper proportions to a drinking vessel and wherein the drinking vessel will be placed under the control of the purchaser after the coin has been deposited in the machine so that the contents of the vessel may be drunk.

It is also my purpose to provide a machine of the type set forth wherein the syrup and the charge of carbonated water will be delivered to individual drinking cups that are automatically placed in cup holders so that each purchaser will obtain his or her drink in a fresh cup, and wherein the cup holders will be automatically dumped after the purchaser has placed the cup holder back in the machine so that the soiled drinking cup will be discharged from the holder and the holder be in condition to receive a fresh cup.

Another object of my invention is the provision of a coin controlled automatic soda water dispensing machine wherein slugs, etc., inserted in the machine with intent to defraud will be thrown out of the machine without setting the dispensing apparatus in operation, which will be entirely automatic in operation and which will be automatically closed up and rendered inactive after the purchaser has drunk the contents of his cup and placed the cup holder back in the machine.

With the above and other objects in view, the invention consists in the construction, combination and arrangement of parts here-

inafter set forth in and falling within the scope of the claims.

In the accompanying drawings; 55

Figure 1 is a view in front elevation of an automatic liquid dispensing machine constructed in accordance with my present invention.

Fig. 2, is a sectional view therethrough 60 looking from front to rear showing the parts in normal or inactive position.

Fig. 3 is a similar view showing the parts in active position.

Fig. 4 is an enlarged vertical sectional 65 view through the individual cup container and the mechanism for delivering the cups to the cup holders.

Fig. 5 is a similar view showing the mechanism in operation. 70

Fig. 6 is an enlarged top plan view of a detail of the mechanism shown in Figs. 4 and 5.

Fig. 7 is a sectional view on the line 7—7 of Fig. 6. 75

Fig. 8 is an enlarged fragmentary horizontal sectional view through the machine showing the turn table and associated parts in top plan.

Fig. 9 is an enlarged fragmentary trans- 80 verse vertical sectional view through the machine showing the turn table and its associated parts.

Fig. 10 is an enlarged horizontal fragmentary sectional view showing the coin controlled connection between the operating means and the valves. 85

Fig. 11 is an enlarged fragmentary vertical sectional view through the coin receiving mechanism. 90

Fig. 12 is a sectional view on the line 12—12 of Fig. 11, showing the parts in inactive position.

Fig. 13 is a similar view on the line 13—13 of Fig. 11 showing the parts in active position. 95

Fig. 14 is a sectional view through one of the syrup controlling valves showing the valve in one position.

Fig. 15 is a similar view showing the valve 100 in its other position.

Fig. 16 is a like view through the carbonated water controlling valve.

Referring now to the drawings in detail,

1 designates a casing constructed of any suitable material and of any desired shape and having the front wall thereof formed with an outwardly projecting vertical portion 2 of a height less than the similar dimension of the casing. In the present instance, the top of the outwardly projecting portion of the casing 2 (Fig. 9) is closed by means of a cover 3 hinged at its inner edge to the adjacent portion of the front wall of the casing, while the top portion of the front wall of the outwardly projecting portion 2 is in the form of a hinged section 4 having its lower edge hinged to the remaining portion of the front wall of the outwardly projecting portion 2. When the cover 3 is swung upwardly and the section 4 swung outwardly access may be had to the interior of the casing 1. Secured to the front wall of the casing 1 adjacent to the upper end thereof and to one side are plates 5, each formed with a coin slot 6 registering with a similar slot in the wall of the casing, and an elongated vertical slot 7 registering with a similar slot in the casing. The names of the flavors of the syrups dispensed by the machine are preferably inscribed upon these plates, as clearly illustrated in Fig. 1 of the drawings. Leading from each coin slot 6 and projecting downwardly therefrom toward the back wall of the casing 1 is a coin chute 8 and secured to one side of the chute 8 and projecting downwardly therefrom is an arm 9. 10 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 ated water container 38. Leading from the lower ends of the containers 36, 37 and 38 are outlet pipes 39 terminally connected to horizontally disposed measuring devices 40. The measuring devices connected to the outlet pipes of the containers 36 and 37 are in the form of relatively short tubes, each adapted to hold a predetermined quantity of the syrup, while the measuring device 10 connected to the container 38 is in the form of a relatively long cylinder in which is mounted for sliding movement a piston 41 (Fig. 5) provided with a piston rod 42 projecting through the outer end of the cylinder. Interposed between the measuring devices 40 and the respective outlet pipes 39 are controlling valves 43. The valves 43 (Figs. 14 and 15) connected to the containers 36 and 37 are identical in construction and each comprises a casing 44 in which is rotatably mounted a plug 45 having the periphery thereof formed with a groove 46. The casing 44 is connected with the pipe 39 at one point and with the measuring device 40 at an opposite point and is connected with a pipe 47 at a point between the pipe 39 and the measuring device 40. In the normal position (Fig. 14) of the plug 45, the groove 46 establishes communication between the measuring tube 40 and the pipe 47, while in the other position (Fig. 15) of the plug communication between the measuring device and the pipe 47 is cut off and the measuring device placed in communication with the container. The controlling valve of the container 38 embodies a casing 48, as shown in Fig. 16, and a plug 49 rotatably mounted in the casing 48 and formed with a transverse passage 50 and a port 51 at right angles to the passage and communicating therewith. The casing 48 is connected to the pipe 39 at one point and to the long measuring device 40 at an opposite point, while leading from the casing at a point between such connections is a pipe 52. Normally, the plug 49 is in a position to establish communication between the pipe 52 and the long measuring device 40, as shown in Fig. 16, by means of the passage 50 and port 51, while in the other position of the plug, such communication is cut off and communication established between the cylinder and the measuring device 40 and the carbonated water container by way of the passage 50. The pipes 47 and 52 are all connected to a common discharge pipe 53 that extends downwardly and then forwardly into the outwardly projecting portion 2 of the casing. The plugs of the controlling valves 43 are equipped with depending handles 54 and pivotally connected to the lower ends of the handles 54 of the controlling valves of the syrup containers are the upper ends of downwardly inclined links 55 (Figs. 2 and 10) and the lower ends of these links 55 rest in the respective yokes on the rod 24 and are formed with transverse slots that align with the slots 34 in the legs of the respective yokes. Slidably mounted in suitable guides and arranged behind the handles 54 is a horizontal bar 56 equipped with outwardly projecting pins 57 disposed in the path of movement of the handles of the respective syrup controlling valves. Arranged at one end of the bar 56 and spaced apart therefrom is a bearing 58 and slidably mounted in the bearing 58 is a rod 59 having one end pivotally connected to the bar 56 and formed in 80 the upper edge of the rod 59 is a notch 60 adapted to be engaged by the dog end of a lever 61 pivoted between its ends upon a bracket projecting upwardly from the bearing 58 and having the other end thereof 85 pivotally connected to the lower end of a link 62. The upper end of the link 62 is pivotally connected to the horizontal leg of a bell crank lever 63 pivoted upon a suitable bracket and having the other leg thereof 90 projecting upwardly and pivotally connected to one end of a rod 64. The other end of the rod 64 is slidably mounted in a bearing 65 carried by the other end wall of the casing and formed on the end of the rod 64 95 beyond the bearing 65 is a lug 66 to which is connected one end of a retractile spring 67, the other end of the spring being secured to the bearing 65. This spring 67 acts upon the rod 64 to hold the dog end of 100 the lever 61 normally in frictional engagement with the upper edge of the rod 59 so that when the rod 59 is moved under the action of the bar 56, the dog end of the lever 61 will drop into the notch 60 and 105 hold the rod 59 against return to normal position. A spring 68 has one end connected to the rod end of the bar 56 and the other end secured to the bracket carried by the bearing 58 and this spring acts to hold the 110 bar 56 in normal position and to restore the same and the rod 59 to such position succeeding the release of the rod 59 by the dog end of the lever 61. The lower end of the handle of the valve controlling the flow of 115 carbonated water from the container 38 is pivotally connected to the adjacent end of the bar 56, as clearly illustrated in Figs. 2 and 3 of the drawings.

When a coin passes to the lower end of 120 either one of the chutes 8, such coin lodges in the groove in the particular link 55 and the alining grooves in the yoke on the rod 24, thereby connecting the link 55 to the rod 24 so that the link will move with the rod. 125 After the coin has been thus positioned, the pedal extremity of the lever 28 is depressed, thereby pulling downwardly upon the cord

27 with the effect to swing the bell crank lever 26 against the action of the spring 32. In this movement of the bell crank lever 26, motion is transmitted through the connecting rod 25 to the bar 24 with the effect to slide the latter along the blocks 23 and in this movement of the bar 24 the particular syrup valve is operated from the position shown in Fig. 14 to the position shown in 10 Fig. 15 so that the syrup may flow from the particular container into the corresponding measuring device. In the movement of the handle of the syrup valve to actuate the latter, such handle engages the adjacent pin 15 57 and slides the bar 56 and the rod 59 against the action of the spring 68. In the movement of the bar 56, the handle of the carbonated water valve connected to such bar is swung with the effect to operate the 20 carbonated water valve out of the position shown in Fig. 16 to cut off communication between the carbonated water measuring device and the pipe 52 and establish communication between the carbonated water container 38 and the measuring device. In the movement of the rod 59 under the action of the bar 56, as just described, the dog end of the lever 61 engages in the notch 60 and holds the bar 56 and the operated valves in 25 30 operated position against the action of the spring 68. When the particular syrup valve and the carbonated water valve are thus operated syrup and the carbonated water flow into the respective measuring devices and 35 as the carbonated water enters its measuring device, the piston 41 is moved outwardly under the action of such water, thereby sliding the piston rod 42 beyond the outer end of the cylinder.

40 The outer end of the piston rod 42 is connected with a cross head 68' slidably mounted in horizontal guides 69 spaced apart vertically, and connected to the cross head 68 is a vertical bar 70 having the upper end 45 thereof adapted to engage a stop 71 fastened upon the rod 64. The upper end of the bar 70 engages the stop 71 as soon as the piston 41 has completed its movement in the cylinder under the action of the carbonated 50 water and when the stop 71 is so engaged the rod 64, the bell crank lever 63, the link 62 and the dog lever 61 are actuated against the action of the spring 68 so that the rod 59 is relieved of the influence of the dog lever 61 55 to permit the spring 68 to react to restore the parts to normal position. In this operation, the syrup and the carbonated water in the respective measuring devices are discharged into the delivery pipe 53. Suitable 60 means is provided for imparting positive movement to the piston 41 so as to discharge the carbonated water from the measuring device under pressure. In the present instance, this means embodies a weight 72 connected through the medium of a cord 73,

trained over a guide sheave 74, with the upper end portion of the bar 70. Thus, positive motion is imparted to the piston rod and the piston to force the carbonated water out of the measuring device.

70 Suitably mounted in the casing 1 below the blocks 23 is a shelf 75 and mounted upon the shelf 75 is a coin receptacle 76 alining with the space between the confronting ends of the blocks 23 and establishing communication between the outer end of the block 23 corresponding to the container 36, and the coin receptacle is a chute 77. When the link 55 on the handle 54 of the controlling valve of the container 37 is connected to the particular yoke on the rod 24 through the medium of a coin and the rod 24 and link 55 are moved over the corresponding block 23 to actuate the apparatus, as previously described, the coin registers with the space between the confronting ends of the blocks 23 so that as soon as the valve of the container 37 has been fully operated the coin will be relieved of the binding action between the link 55 and the yoke and drop through the spaces between the confronting ends of the blocks 23 into the coin receptacle 76. When the link connected to the controlling valve of the container 36 is connected to the particular yoke on the bar 24 by a coin, and the valve is fully open, as previously described, the coin rides beyond the outer end of the corresponding block 23 and when relieved of the binding action of the link and yoke drops into the chute 77 and passes down the chute into the coin container 78.

105 Suitably supported in the casing 1 immediately adjacent to the outwardly projecting portion 2 and disposed at a point approximately centrally of the width of the outwardly projecting portion 2 of the casing are vertically alining bearings 78 and journaled in these bearings is a vertical shaft 79 capable of rotation and fixed upon the shaft 79 and adapted to rotate therewith is a turn table 80 disposed at a height convenient to the reach of a purchaser. In the present instance, this turn table 80 is formed with radial slots 81 opening onto the periphery thereof and spaced apart equal distances around the turn table and mounted in the respective slots 81 are plates 82 having the inner ends hinged to the corresponding end walls of the slots 81, and the outer ends equipped with rollers 83. Suitably supported in the casing and disposed in a plane immediately below that of the turn table is a stationary table 84 formed centrally with an opening corresponding in diameter to the diameter of the turn table 110 80, and the inner portion thereof, that is, the part projecting into the casing 1 from the portion 2, cut away, as clearly illustrated in Fig. 8 of the drawings. 85 designates a curved restoring bar having the ends there- 115 120 125 130

of secured to the ends of the stationary table 84 at the cut out portion thereof and one end of this restoring bar is disposed downwardly and inwardly of the corresponding 5 end of the stationary table at the cut out portion thereof, while the other end of the bar is inclined upwardly and merges into the remaining end of the stationary table at the cut out portion thereof. Fixed upon 10 the upper end of the shaft 79 is a ratchet wheel 86, while loosely mounted upon the upper end of the shaft above the ratchet wheel is a lever 87 equipped with a spring actuated dog 88 normally held in engagement with the ratchet wheel 86. In the 15 present instance, the number of teeth on the ratchet wheel corresponds to the number of plates 82 on the turn table and these teeth are spaced apart equal distances to correspond to the spacing of the plates. Pivotally connected to one end of the lever 87 is one extremity of a connecting rod 89 and the remaining end of the rod 89 is pivotally secured to the lower end of a lever 90 fulcrumed between its ends upon a bracket 91 carried by the casing. The upper end of the lever 90 is connected through the medium of a link 92 with the lower end of the bar 70, as clearly illustrated in Figs. 2 20 and 3 of the drawings. Mounted upon the plates 82 respectively are cup holders 93 and, in the present instance, these cup holders 93 are held against removal from the machine by means of cords 94 secured to the lower ends of the respective cup holders and projecting through openings 95 in the plates 25 82. These cords 94 are of suitable length and fastened to the lower end of each cord is a weight 96. By means of the cords 94 the cup holders may be lifted from the turn 30 table to facilitate drinking and when the cup holder is released the weight 96 restores the holder to the corresponding plate 82.

In the outward movement of the bar 70 45 under the action of the piston 41 in the carbonated water measuring device, the lower end of the bar 70 connected to the upper end of the lever 90 swings such lever with the effect to rotate the lever 87 through the 50 medium of the rod 89. In this rotation of the lever 87 the dog 88 engages the adjacent tooth of the ratchet wheel 86 and revolves the latter and the turn table 80 through an angle sufficient to move the cup holder 93 55 that is in line with the discharge pipe 53 out of alinement with such pipe, and bring the next holder 93 into alinement with the pipe. As the turn table revolves, the plate 82 carrying the cup holder previously in 60 line with the discharge pipe rides off of the stationary table 84 and drops down so that an article in the cup holder will be discharged therefrom, as clearly illustrated in Figs. 2 and 3 of the drawings, and in the 65 continued rotation of the turn table, the

cord 94 of the cup holder on the fallen plate rides around on the inside of the bar 85, while the plate rides around on the outside of the bar and is gradually restored to normal position and engaged with the upper 70 surface of the table 84 at the other end thereof. Thus, each time that the lever 90 is swung under the action of the outwardly moving bar 70, the turn table 80 is rotated to move one cup holder out of line with 75 the discharge pipe and another cup holder into line with such pipe.

Mounted upon the shelf 75 is a container 80 carrying individual drinking cups, and a delivery mechanism for delivering the cups 85 successively to the cup holders 93 immediately preceding the movement of the cup holders into line with the discharge pipe 53. Secured to the shelf 75 and projecting upwardly therefrom immediately in line with 85 the cup holder following that alining with the pipe 53 is a tubular container 97 having the lower end alining with an opening 90 formed in the shelf 75 and secured to the under side of the shelf 75 around the opening therein is a ring 98 formed of some flexible material and having the inner edge projecting into the opening to form a seat for the bottom cup in the container 97. The cups are indicated at 99 and are preferably 95 composed of paraffin paper although any other suitable material may be used and these cups are nested with the open ends up and the lowermost cup is supported by the inwardly projecting edge of the ring 98 in 100 position to enter the alining cup holder 93.

The delivery mechanism for removing the cups from the container one after another and delivering such cups to the cup holders successively is constructed as follows: Secured to the shelf 75 and projecting upwardly therefrom behind the tubular container 97 is a baseboard 100 and secured to the front face of the baseboard 100 and alining vertically with each other are guides 110 101 in which is slidably mounted a vertical bar 102 having the upper end portion formed with an elongated slot 103. Fasted to the bar 102 immediately below the slot 103 is a cross bar 104 and arranged 115 below the cross bar 104 is a second cross bar 105 secured to the vertical bar 102 adjacent to the lower end thereof. Pivotaly connected to the outer ends of the cross bar 105 are vertical levers 106 spaced apart in 120 parallelism and having the lower ends projecting through slots formed in the shelf 75 and the upper ends projecting slightly above the cross bar 104 and disposed in juxtaposition to one side of such cross bar. 125 Secured to the cross bar 104 and projecting outwardly therefrom are pins 107 disposed at the opposite side edges of each lever 106 and at the ends of the path of movement of such lever. Pivotaly connected to the 130

upper ends of the levers 106 and projecting upwardly therefrom are links 108 having the upper ends thereof pivotally connected to each other and to a ring 109. One end of the pivot pin, connecting the links 108 to each other, and to the ring 109, is passed through the slot 103. Formed in one edge of the bar 102 are oppositely inclined notches 110 and 111 arranged one above the other and pivotally mounted between its ends upon the baseboard 100 is a lever 112 having one end provided with an outwardly extending pin 113 adapted to enter either one of the notches 110, 111 and the other end connected with a spring 114 acting to hold the pin 113 normally in the particular notch. The lower ends of the levers 106 are formed with outwardly projecting feet 115 respectively arranged at diametrically opposite sides of the bottom cup in the container 97 and secured to the upper edges of the respective feet 115 and projecting upwardly therefrom are pins 116 upon which are mounted plates 117 alining with each other longitudinally and disposed upon opposite sides of the bottom cup. The inner edges of the plates 117 are concaved to conform to the curvature of the side wall of the cup and are formed with prongs 118 adapted to bite into the cup. The outer ends of the plates 117 are formed with upwardly projecting lugs 119. Placed in face to face contact with the upper surface of each plate 117 is what may be termed a clearing plate 120 having the side edges thereof turned under the plate 117, as clearly illustrated in Fig. 7 of the drawings, so that the plate 120 will be held upon the plate 117 and at the same time permitted to slide longitudinally upon such plate. The inner edges of the clearing plates 120 are cut to conform to the shape of the pronged edges of the plates 117, while the outer ends of the clearing plates are formed with upstanding lugs 121 and interposed between the lugs 119 and 121 are coiled expansion springs 122 that act to hold the inner edges of the clearing plates normally over the prongs 118. In the present instance, the side edges of each clearing plate 120 adjacent to the inner end of the plate are cut away as at 123 to form shoulders 124 and secured to the upper face of the plate 117 in the path of the shoulders 124 are stop pins 125 that act to limit the movement of the plate 120 under the action of the spring 122.

Journalized in suitable bearings carried by the upper end of the casing 1 is a shaft 126 and fixed upon one end of the shaft 126 is an arm 127 having the outer end thereof connected to the ring 109 at a point diametrically opposite to the connection between the ring and the links 108. Fixed upon the other end of the shaft 126 is an

arm 128 connected to one end of a rod 129 and the remaining end of the rod 129 terminates adjacent to the upper end of the bar 70 and is formed with an elongated slot 130 through which is passed a pin 131 carried by the upper end of the bar 70. 132 indicates a spring having one end fastened to the arm 128 and the other end secured to a lug 133, the spring acting to hold the shaft 126 in normal position and to restore the same to such position. 75

In the outward movement of the bar 70 under the action of the carbonated water entering the cylinder of the measuring device, the pin 131 rides along the slot 130 and engages one end wall of the slot with the effect to pull the rod 129 and swing the shaft 126 against the action of the spring 132, previous to the rod 70 engaging the stop 71. In this movement of the shaft 126, the arm 127 is lowered from the position shown in Fig. 4 to the position shown in Fig. 5 and in the initial downward movement of the arm 127 the pin rides down in the slot 103 and the links 108 spread apart to swing the upper ends of the levers 106 outwardly and the lower ends inwardly. In this movement of the levers 106, the pronged edges 118 of the plates 117 bite into the material of the lowermost cup in the container 97, the plates 120 being forced outwardly against the action of the springs 122, by the material of the cup, to uncover the prongs. As soon as the levers 106 have completed this movement, the upper ends thereof engage the outermost pins 107, thereby checking the swinging of the levers and causing the latter to move downwardly in the continued downward movement of the arm 127. In this downward movement 105 of the levers 106, the bar 102 is likewise actuated and the pin 113 rides out of the lowermost notch 111 and into the top notch 110. As the lower ends of the levers move down the bottom cup is carried out of the container and into the alining cup holder 93. In the continued outward movement of the bar 70 the rod 64 is pulled to release the valves, as previously described, and upon the release of the valves the bar 70 moves 115 inwardly and releases the rod 129 so that the spring 132 may react to restore the parts of the cup delivery mechanism to normal position. In the swinging movement of the levers 106 to normal position, the cup is released and drops into the alining cup holder 93, while in the upward movement of the levers 106 the bar 102 is carried upwardly against the action of the pin 113 and the spring 114, and the notch 110 rides out of 125 engagement with the pin, while the notch 111 receives the pin. In the initial swinging of the levers 106 to normal position, the springs 122 react and slide the plates 120 over the prongs 118 so as to force the cup 130

out of engagement with the prongs. The cup delivery mechanism is placed in operation immediately succeeding the rotation of the turn table under the action of the lever 90, the connecting rod 89 and the pawl and ratchet, so that the used cup in the holder in line with the discharge pipe will be thrown out of the holder incident to the plate 82 swinging downwardly, the next adjacent cup holder and cup therein moved into line with the discharge pipe and the following cup holder moved into position beneath the cup container to receive a fresh cup from the container.

15 I will now proceed to describe the mechanism for opening the section 4 and the cover 3 and for holding the same open. In the present instance, this mechanism embodies a bell crank lever 134 pivotally mounted upon a bracket 135 arranged above the turn table 80 and to one side thereof. One leg of the bell crank lever 134 projects upwardly and rearwardly and is pivotally connected to the lower end of a vertical bar 136, such bar having the upper end formed with an elongated slot 137. The other leg of the bell crank lever 134 is offset from the first-mentioned leg and projects downwardly and rearwardly and is connected with one end of a rod 138 projecting into the portion 2 of the casing and having the other end thereof pivotally connected to the section 4. A link 139 has one end connected to the rod 138 and the other extremity pivotally secured to the under surface of the cover 3. 140 designates a bell crank lever pivoted adjacent to the guides 69 and having one end adjustably connected through the medium of a link 141 with a bar 70 and the other end connected to a block 142 slidably mounted in the slot 137 of the bar 136. Pivotally connected to the upwardly projecting leg of the bell crank lever 134 is the upper end of a connecting link 143 and the lower end of this link is pivotally secured to the upper end of a rod 144. The lower end of the rod 144 is connected to a block 145 slidably mounted upon vertical guide rods 146 secured to a baseboard 147 upstanding from the bottom of the casing.

1. Pivot to a bracket 148 carried by the lower end of the baseboard 147 is a vertical lever 149 having the upper end formed with a latching dog 150 and the lower end formed 55 with an outwardly projecting horizontally disposed lug 151 connected through the medium of a spring 152 with the bottom wall of the casing.

As the bar 70 moves outwardly under the action of the carbonated water entering the cylinder of the measuring device 40 the bell crank lever 140 is swung and the block 142 moves downwardly in the slot 137 and engages the lower end wall of such slot and 65 as soon as the block engages the lower end

wall of the slot, motion is transmitted to the bar 136 and the bell crank lever 134, thereby swinging such lever with the effect to move the rod 138 and the link 139 to swing the section 4 and the cover 3 to open position. Simultaneously with this movement of the bell crank lever 134, the connecting link 143 slides the rod 144 downwardly and in the downward movement of the rod 144, the block 145 slides along the 75 guide rods 146 and engages beneath the latching dog 150 on the lever 149, thereby holding the section 4 and the cover 3 in open position so that the purchaser may lift the cup holder from the turn table and 80 drink the contents of the cup.

Secured to the bottom wall of the casing 1 and extending upwardly therefrom is a vertical bar 153 formed with a vertical slot 154 and pivotally connected to the lower 85 end of the lever 149 immediately above the lug 151 is one end of a latching bar 155. The other end of the bar 155 is passed through the slot 154 and capable of sliding movement therein. Pivotally connected to one side of the bar 153 adjacent to the upper end thereof is a spring actuated holding dog 156 connected through the medium of a link 157 with a drip pan 158 pivoted upon a rod 159 and held in normal position by means of a spring 160. Surrounding the drip pan 158 is a guard 161 formed with a stop 162 disposed in the path of movement of one end of the drip pan 158 to limit the movement of such pan under the 95 action of the spring 160. 163 designates a rope or other flexible element having one end connected to the latching bar 155 and the other end trained over a suitably arranged guide shâve 164 and connected to the lower end of the bar 70. Simultaneously with the opening of the section 4 and the cover 3, the bar 70 pulls upon the rope 163, thereby elevating the latching bar 155 to engage the end of such bar in the slot 154 with the spring actuated dog 156 so as to hold the bar 155 elevated. The guard 161 prevents the weights 96 from coming in contact with the pan 158. When, however, the filled cup holder is lifted from the turn 110 table 80, the weight 96 connected thereto is relieved of the influence of the guard 161 and when the cup holder is replaced on the table the weight drops onto the pan 158, thereby swinging the latter to disengage 115 the dog 156 from the latching bar 155 and owing to the slack in the rope 163 incident to the return of the bar 70 to normal position, as hereinbefore described, the latching bar 155 gravitates to horizontal position 125 and strikes the lug 151 with the effect to swing the lever 149 and disengage the dog 150 from the block 145, thereby releasing the section 4 and the cover 3. A spring 165 is connected to the bell crank lever 134. 130

and acts to move the section 4 and the cover 3 to closed position immediately succeeding the release thereof, thereby closing up the machine and necessitating the insertion 5 of another coin to again place the machine in operation.

In the present instance, the bell crank lever 134 is held against movement previous to the opening of the carbonated water 10 valve so as to prevent tampering with the machine and this holding device for the bell crank lever 134 embodies, in this form of my invention, a horizontal rod 166 slidably mounted in suitable guides 167 and having 15 one end formed with a hook 168 adapted to engage the upwardly and rearwardly projecting leg of the bell crank lever 134, and the other end formed with a shoe 169 disposed in the path of movement of the handle 20 of the carbonated water valve, as clearly shown in Figs. 2 and 3 of the drawings. 170 designates a spring having one end connected to the rod 166 and the other end fastened to one of the bearings 167 and this 25 spring acts to restore the rod 166 to normal position succeeding the return of the valves to normal position.

From the foregoing description taken in connection with the accompanying drawings, 30 the construction and mode of operation of my improved automatic liquid dispensing machine will be readily apparent. It will be seen that I have provided a machine which is entirely automatic in operation and whereby a syrup of the desired flavor and a charge of carbonated water, in the proper proportions, may be delivered 35 to a cup and the cup placed within the reach of the purchaser, and wherein a fresh cup 40 will be moved into position to receive the liquid in each operation of the machine.

While I have herein shown and described the preferred form of my invention by way 45 of illustration, I wish it to be understood that I do not limit or confine myself to the precise details of construction herein described and delineated, as modification and variation may be made within the scope of the claims and without departing from the 50 spirit of the invention. Furthermore, I wish it to be understood that any number of syrup containers and their associated parts may be employed, while adjustable connections between the parts may be used 55 wherever desired or necessary.

I claim:

1. In automatic liquid dispensing apparatus, a syrup container, a carbonated water container, measuring devices connected to 60 said containers respectively, a discharge spout connected to said measuring devices, valves controlling communication between said containers and measuring devices and between said measuring devices and spout 65 and normally in positions to cut off com-

munication between said containers and measuring devices and establish communication between said measuring devices and spout, and means for operating said valves to establish communication between said 70 containers and measuring devices.

2. In automatic liquid dispensing apparatus, a syrup container, a carbonated water container, measuring devices connected to 75 said containers respectively, a discharge spout connected to said measuring devices, valves controlling communication between said containers and measuring devices and between said measuring devices and spout and normally in positions to cut 80 off communication between said containers and measuring devices and establish communication between said measuring devices and spout, means for operating said valves to establish communication between said containers and measuring devices, and means for restoring said valves to normal positions whereby communication between said 85 measuring devices and containers will be cut off and the liquid in said measuring devices delivered to said discharge spout.

3. In automatic liquid dispensing apparatus, syrup containers, a carbonated water container, measuring devices connected to 90 said containers respectively, a discharge pipe common to said measuring devices, valves controlling communication between said containers and measuring devices and between said measuring devices and spout, and normally in positions to cut off communication between said containers and 95 measuring devices and establish communication between said measuring devices and spout, means whereby said carbonated water valve may be operated in the operation of 100 any one of said syrup valves, and means for selectively operating said syrup valves.

4. In automatic liquid dispensing apparatus, syrup containers, a carbonated water container, measuring devices connected to 110 said containers respectively, a discharge pipe common to said measuring devices, valves controlling communication between said containers and measuring devices and between said measuring devices and spout, and normally in positions to cut off communication between said containers and 115 measuring devices and establish communication between said measuring devices and spout, means whereby said carbonated water valve may be operated in the operation of 120 any one of said syrup valves, and coin controlled mechanism for selectively operating said syrup valves.

5. In automatic liquid dispensing apparatus, a delivery pipe having an inlet end and a discharge end, a horizontal turn table below the discharge end of said delivery pipe and rotatable about a vertical axis, and cup holders on said turn table movable into 125 130

alinement with the discharge end of said pipe successively.

6. In automatic liquid dispensing apparatus, a delivery pipe having an inlet end and a discharge end, cup holders arranged in a circle and movable into alinement with the discharge end of said pipe, and means for delivering individual drinking cups to said holders as the latter are brought into alinement with said delivery pipe.

10 7. In automatic liquid dispensing apparatus, a vertical delivery pipe having an inlet end and a discharge end, a rotary table, cup holders mounted upon said table and
15 arranged in a circle thereon, and movable into alinement with the discharge end of said pipe successively, and means for delivering individual drinking cups to said holders as the latter are brought into alinement
20 with said delivery pipe.

20 8. In automatic liquid dispensing apparatus, a delivery pipe having an inlet end and a discharge end, cup holders movable into alignment with the discharge end of
25 said delivery pipe successively, means for delivering individual drinking cups to said holders as the latter are brought into alignment with the discharge end of the pipe, and means for dumping said holders to discharge the cup therefrom succeeding the
30 drinking of the contents of the cup.

9. In automatic liquid dispensing apparatus, a delivery pipe having an inlet end and a discharge end, cup holders movable into alignment with the discharge end of said pipe successively, and means for delivering individual cups to said holders before the latter are brought into line with said delivery pipe.

40 10. In automatic liquid dispensing apparatus, a delivery pipe having an inlet end and a discharge end, a turn table, cup holders mounted on said turn table and movable therewith into alignment with the discharge
45 end of said pipe successively, and means for delivering the individual cups to said holders immediately preceding the alining of the holders with the delivery pipe.

11. In automatic liquid dispensing apparatus, a delivery pipe having an inlet end and a discharge end, a turn table, cup holders mounted on said turn table and movable therewith into alignment with the discharge end of said pipe successively, means for delivering the individual cups to said holders immediately preceding the alining of the holders with the delivery pipe, and a loose connection between said holders and turn table whereby the holders may be lifted from the table to facilitate the drinking of the contents of said cups.

12. In automatic liquid dispensing apparatus, a delivery pipe having an inlet end and a discharge end, a turn table, cup holders mounted on said turn table and movable

therewith into alinement with the discharge end of said pipe successively, means for delivering the individual cups to said holders immediately preceding the alining of the holders with the delivery pipe, a loose connection between said holders and turn table whereby the holders may be lifted from the table to facilitate the drinking of the contents of said cups, and means for dumping said holders to discharge the cups therefrom succeeding the drinking of the contents of the cups.

13. In automatic liquid dispensing apparatus, a delivery pipe having an inlet end and a discharge end, a turn table, cup holders mounted on said turn table and movable therewith into alinement with the discharge end of said pipe successively, means for delivering the individual cups to said holders immediately preceding the alining of the holders with the delivery pipe, a loose connection between said holders and turn table whereby the holders may be lifted from the table to facilitate the drinking of the contents of the cups, and means controlled by the movement of said turn table for dumping said cup holders to discharge the cups therefrom succeeding the drinking of the contents of the cups.

14. In automatic liquid dispensing apparatus, a delivery pipe having an inlet end, and a discharge end, cup holders movable into alignment with the discharge end of said pipe successively, a container holding a stack of individual drinking cups, and means for delivering the drinking cups individually to said holders before the latter are moved into position to receive the contents of said pipe.

15. In automatic liquid dispensing apparatus, a delivery pipe having an inlet end and a discharge end, cup holders movable into alignment with the discharge end of said pipe successively, a container holding a stack of individual drinking cups, and automatic mechanism for engaging the lowermost cup in the bottom of the stack and moving said cup downwardly and then releasing the cup whereby the latter may fall into the alining cup holder.

16. In automatic liquid dispensing apparatus, a syrup container, a carbonated water container, measuring devices connected to said containers respectively, a discharge pipe common to said measuring devices, valves establishing communication between said containers and measuring devices and between said measuring devices and spout and normally in positions to cut off communication between said containers and measuring devices and establish communication between said measuring devices and spout, means for operating said valves to establish communication between said containers and measuring devices and cut off 12

- communication between said measuring devices and pipe, means for restoring said valves to normal position whereby the contents of said measuring devices will be delivered to said discharge pipe, and cup holders movable into alignment with said discharge pipe successively immediately preceding the return of said valves to normal positions.
17. In automatic liquid dispensing apparatus, a syrup container, a carbonated water container, measuring devices connected to said containers respectively, a discharge pipe common to said measuring devices, valves establishing communication between said containers and measuring devices and between said measuring devices and spout and normally in positions to cut off communication between said containers and measuring devices and establish communication between said measuring devices and spout, means for operating said valves to establish communication between said containers and measuring devices and cut off communication between said measuring devices and pipe, means for restoring said valves to normal positions whereby the contents of said measuring devices will be delivered to said discharge pipe, cup holders movable into alignment with said discharge pipe successively immediately preceding the return of said valves to normal positions, said carbonated water measuring device embodying a cylinder, a piston in the cylinder movable therein under the action of the carbonated water entering the cylinder, means connected to said piston and operable in said movement thereof to actuate said cup delivery means, and means for operating said piston in the reverse direction to discharge the carbonated water through said valve to said delivery pipe.
18. In automatic liquid dispensing apparatus, a syrup container, a carbonated water container, measuring devices connected to said containers respectively, a discharge pipe common to said measuring devices, valves establishing communication between said containers and measuring devices and between said measuring devices and spout and normally in positions to cut off communication between said containers and measuring devices and establish communication between said containers and measuring devices and cut off communication between said measuring devices and pipe, means for restoring said valves to normal positions whereby the contents of said measuring devices will be delivered to said discharge pipe, cup holders movable into alignment with said discharge pipe successively immediately preceding the return of said valves to normal positions, said carbonated water measuring device embodying a cylinder, a piston in the cylinder movable therein under the action of the carbonated water entering the cylinder, and means connected to said piston and operable in said movement thereof to actuate said cup delivery means.
19. In automatic liquid dispensing apparatus, a syrup container, a carbonated water container, measuring devices connected to said containers respectively, a discharge pipe common to said measuring devices, valves establishing communication between said containers and measuring devices and between said measuring devices and spout and normally in positions to cut off communication between said containers and measuring devices and establish communication between said measuring devices and spout, means for operating said valves to establish communication between said containers and measuring devices and cut off communication between said measuring devices and pipe, means for restoring said valves to normal positions whereby the contents of said measuring devices will be delivered to said discharge pipe, cup holders movable into alignment with said discharge pipe successively immediately preceding the return of said valves to normal positions, said carbonated water measuring device embodying a cylinder, a piston in the cylinder movable therein under the action of the carbonated water entering the cylinder, means connected to said piston and operable in said movement thereof to actuate said cup delivery means, means for operating said piston in the reverse direction to discharge the carbonated water through said valve to said delivery pipe.

- delivery pipe, and means operable from said piston in the last movement thereof to move said cup holders.
21. In automatic liquid dispensing apparatus, a syrup container, a carbonated water container, measuring devices connected to said containers respectively, a discharge pipe common to said measuring devices, valves establishing communication between said containers and measuring devices and between said measuring devices and spout and normally in positions to cut off communication between said containers and measuring devices and establish communication between said measuring devices and spout, means for operating said valves to establish communication between said containers and measuring devices and cut off communication between said measuring devices and pipe, means for restoring said valves to normal positions whereby the contents of said measuring devices will be delivered to said discharge pipe, cup holders movable into alinement with said discharge pipe successively immediately preceding the return of said valve to normal positions, said carbonated water measuring device embodying a cylinder, a piston in the cylinder movable therein under the action of the carbonated water entering the cylinder, means connected to said piston and operable in said movement thereof to actuate said cup delivery means, means for operating said piston in the reverse direction to discharge the carbonated water through said valve to said delivery pipe, means operable from said piston in the filling movement thereof to move said cup holders, a casing inclosing said apparatus and formed with an opening in juxtaposition to said cup holders, a cover for said opening normally closed, means operable from said piston in the filling movement thereof and connected to said door to swing the latter to open position, and means for latching said door in open position.
22. In automatic liquid dispensing apparatus, a syrup container, a carbonated water container, measuring devices connected to said containers respectively, a discharge pipe common to said measuring devices, valves establishing communication between said containers and measuring devices and between said measuring devices and spout and normally in positions to cut off communication between said containers and measuring devices and establish communication between said measuring devices and spout, means for operating said valves to establish communication between said containers and measuring devices and cut off communication between said measuring devices and pipe, means for restoring said valves to normal positions whereby the contents of said measuring devices will be delivered to said discharge pipe, cup holders movable into alinement with said discharge pipe successively immediately preceding the return of said valves to normal positions, said carbonated water measuring device embodying a cylinder, a piston in the cylinder movable therein under the action of the carbonated water entering the cylinder, means connected to said piston and operable in said movement thereof to actuate said cup delivery means, means for operating said piston in the reverse direction to discharge the carbonated water through said valve to said delivery pipe, means operable from said piston in the filling movement thereof to move said cup holders, a casing inclosing said apparatus and formed with an opening in juxtaposition to said cup holders, a cover for said opening normally closed, means operable from said piston in the filling movement thereof and connected to said door to swing the latter to open position, and means for latching said door in open position.
23. In automatic liquid dispensing apparatus, a syrup container, a carbonated water container, measuring devices connected to said containers respectively, a discharge pipe common to said measuring devices, valves establishing communication between said containers and measuring devices and between said measuring devices and spout and normally in positions to cut off communication between said containers and measuring devices and establish communication between said measuring devices and spout, means for operating said valves to establish communication between said containers and measuring devices and cut off communication between said measuring devices and pipe, means for restoring said valves to normal positions whereby the contents of said measuring devices will be delivered to said discharge pipe, cup holders movable into alinement with said discharge pipe successively immediately preceding the return of said valves to normal positions, said carbonated water measuring device embodying a cylinder, a piston in the cylinder movable therein under the action of the carbonated water entering the cylinder, means connected to said piston and operable in said movement thereof to actuate said cup delivery means, means for operating said piston in the reverse direction to discharge the carbonated water through said valve to said delivery pipe, means operable from said piston in the filling movement thereof to move said cup holders, a casing inclosing said apparatus and formed with an opening in juxtaposition to said cup holders, a cover for said opening normally closed, means operable from said piston in the filling movement thereof and connected to said door to swing the latter to open position, and means for latching said door in open position.

whereby the door may be restored to closed position.

24. In automatic liquid dispensing apparatus, a delivery pipe having an inlet end and a discharge end, cup holders movable into alinement with the discharge end of said pipe successively, means for delivering individual cups to said holders successively previous to the holders alining with the pipe, a movable table carrying said holders, a loose connection between said holders and table so that the holders may be lifted from the table to facilitate the drinking of the contents of the cups, a casing inclosing said apparatus and formed with an opening in juxtaposition to said cup holders, and a door normally closing said opening.

25. In automatic liquid dispensing apparatus, a delivery pipe having an inlet end and a discharge end, cup holders movable into alinement with the discharge end of said pipe successively, means for delivering individual cups to said holders successively previous to the holders alining with the pipe, a movable table carrying said holders, a loose connection between said holders and table so that the holders may be lifted from the table to facilitate the drinking of the contents of the cups, a casing inclosing said apparatus and formed with an opening in juxtaposition to said cup holders, a door normally closing said opening, and means for opening said door automatically during the filling of the cups.

35 26. In automatic liquid dispensing apparatus, a delivery pipe having an inlet end and a discharge end, cup holders movable into alinement with the discharge end of said pipe successively, means for delivering individual cups to said holders successively previous to the holders alining with the pipe, a movable table carrying said holders, a loose connection between said holders and table so that the holders may be lifted from the table to facilitate the drinking of the contents of the cups, a casing inclosing said apparatus and formed with an opening in juxtaposition to said cup holders, a door normally closing said opening, means for opening said door automatically during the filling of the cups, and means for automatically latching said door in open position.

27. In automatic liquid dispensing apparatus, a delivery pipe having an inlet end and a discharge end, cup holders movable into alinement with the discharge end of said pipe successively, means for delivering individual cups to said holders successively previous to the holders alining with the pipe, a movable table carrying said holders, a loose connection between said holders and table so that the holders may be lifted from the table to facilitate the drinking of the contents of the cups, a casing inclosing said apparatus and formed with an opening in

juxtaposition to said cup holders, a door normally closing said opening, means for opening said door automatically during the filling of the cups, means for automatically latching said door in open position, and means operable from the cup holders when the latter are restored to the table succeeding the drinking of the contents of the cups to release said latching means whereby said door may be restored to closed position.

28. In automatic liquid dispensing apparatus, a delivery pipe having an inlet end and a discharge end, cup holders movable into alinement with the discharge end of said pipe successively, means for delivering individual cups to said holders successively previous to the holders alining with the pipe, a movable table carrying said holders, a loose connection between said holders and table so that the holders may be lifted from the table to facilitate the drinking of the contents of the cups, a casing inclosing said apparatus and formed with an opening in juxtaposition to said cup holders, a door normally closing said opening, means for opening said door automatically during the filling of the cups, means for automatically latching said door in open position, means operable from the cup holders when the latter are restored to the table succeeding the drinking of the contents of the cups to release said latching means whereby said door may be restored to closed position, and means connected to said door for restoring the same to closed position.

29. In automatic liquid dispensing apparatus, a syrup container, a carbonated water container, measuring devices connected to said containers respectively, a discharge pipe connected to said measuring devices, valves controlling communication between said containers and measuring devices and between said measuring devices and pipe and normally in position to cut off communication between said containers and measuring devices and establish communication between said measuring devices and pipe, means for operating said valves to establish communication between said containers and measuring devices and cut off communication between said measuring devices and pipe, means for restoring said valves to normal position whereby the contents of the measuring devices may be delivered to said pipe, and means in said carbonated water measuring device for discharging the water therefrom under pressure succeeding the opening of the syrup valve.

30. In automatic liquid dispensing apparatus, a syrup container, a carbonated water container, measuring devices connected to said containers respectively, a discharge pipe connected to said measuring devices, valves controlling communication between said containers and measuring devices and be-

tween said measuring devices and pipe and normally in position to cut off communication between said containers and measuring devices and establish communication between said measuring devices and pipe, means for operating said valves to establish communication between said containers and measuring devices and cut off communication between said measuring devices and pipe, means for restoring said valves to normal position whereby the contents of the measuring devices may be delivered to said pipe, and means in said carbonated water measuring device movable therein under the action of the incoming carbonated water and operable to discharge the water from said device under pressure in the reverse movement thereof.

31. In automatic liquid dispensing apparatus, a syrup container, a carbonated water container, measuring devices connected to said containers respectively, a discharge pipe connected to said measuring devices, valves controlling communication between said containers and measuring devices and between said measuring devices and pipe and normally in position to cut off communication between said containers and measuring devices and establish communication between said measuring devices and pipe, means for operating said valves to establish communication between said containers and measuring devices and cut off communication between said measuring devices and pipe, means for restoring said valves to normal position whereby the contents of the measuring devices may be delivered to said pipe, means in said carbonated water measuring device movable therein under the action of the incoming carbonated water and operable to discharge the water from said device under pressure in the reverse movement thereof, a turn table below the discharge end of delivery pipe, cup holders on said turn table movable into line with the discharge end of said pipe successively, and means operable from said carbonated water controlled means to rotate said turn table in the filling movement of said carbonated water controlled means whereby a fresh cup holder will be brought into line with said pipe.

32. In automatic liquid dispensing apparatus, a syrup container, a carbonated water container, measuring devices connected to said containers respectively, a discharge pipe connected to said measuring devices, valves controlling communication between said containers and measuring devices and between said measuring devices and pipe and normally in position to cut off communication between said containers and measuring devices and establish communication between said measuring devices and pipe, means for operating said valves to establish communication between said containers and measuring devices and cut off communication between said measuring devices and pipe, means for restoring said valves to normal position whereby the contents of the measuring devices may be delivered to said pipe, means in said carbonated water measuring device movable therein under the action of the incoming carbonated water and operable to discharge the water from said device under pressure in the reverse movement thereof, a turn table below the discharge end of delivery pipe, cup holders on said turn table movable into line with the discharge end of said pipe successively, and means operable from said carbonated water controlled means to rotate said turn table in the filling movement of said carbonated water controlled means whereby a fresh cup holder will be brought into line with said pipe.

communication between said containers and measuring devices and cut off communication between said measuring devices and pipe, means for restoring said valves to normal position whereby the contents of the measuring devices may be delivered to said pipe, means in said carbonated water measuring device movable therein under the action of the incoming carbonated water and operable to discharge the water from said device under pressure in the reverse movement thereof, a turn table below the discharge end of said delivery pipe, cup holders on said turn table movable into line with the discharge end of said pipe successively, means operable from said carbonated water controlled means to rotate said turn table in the filling movement of said carbonated water controlled means whereby a fresh cup holder will be brought into line with said pipe, and means for delivering individual drinking cups to said cup holders previous to the latter alining with said pipe.

33. In automatic liquid dispensing apparatus, a syrup container, a carbonated water container, measuring devices connected to said containers respectively, a discharge pipe connected to said measuring devices, valves controlling communication between said containers and measuring devices and between said measuring devices and pipe and normally in position to cut off communication between said containers and measuring devices and establish communication between said measuring devices and pipe, means for operating said valves to establish communication between said containers and measuring devices and cut off communication between said measuring devices and pipe, means for restoring said valves to normal position whereby the contents of the measuring devices may be delivered to said pipe, means in said carbonated water measuring device movable therein under the action of the incoming carbonated water and operable to discharge the water from said device under pressure in the reverse movement thereof, a turn table below the discharge end of said delivery pipe, cup holders on said turn table movable into line with the discharge end of said pipe successively, and means operable from said carbonated water controlled means to rotate said turn table in the filling movement of said carbonated water controlled means whereby a fresh cup holder will be brought into line with said pipe, and means for delivering individual drinking cups to said cup holders previous to the latter alining with said pipe.

34. In automatic liquid dispensing apparatus, a syrup container, a carbonated water container, measuring devices connected to said containers respectively, a discharge pipe connected to said measuring devices, valves controlling communication between said containers and measuring devices and between said measuring devices and pipe and normally in position to cut off communication between said containers and measuring devices and establish communication between said measuring devices and pipe, means for operating said valves to establish communication between said containers and measuring devices and cut off communication between said measuring devices and pipe, means for restoring said valves to normal position whereby the contents of the measuring devices may be delivered to said pipe, means in said carbonated water measuring device movable therein under the action of the incoming carbonated water and operable to discharge the water from said device under pressure in the reverse movement thereof, a turn table below the discharge end of said delivery pipe, cup holders on said turn table movable into line with the discharge end of said pipe successively, means operable from said carbonated water controlled means to rotate said turn table in the filling movement of said carbonated water controlled means whereby a fresh cup holder will be brought into line with said pipe, means for delivering individual drinking cups to said cup holders previous to the latter alining with said pipe, means operable from said carbonated water controlled means to deliver individual drinking cups to said holders in the filling movement of said carbonated water controlled means immediately preceding the alining of the holders with the pipe, means for dumping said cup holders after each has alined with said pipe to discharge the individual drinking cup therefrom, a casing inclosing said apparatus and formed with an opening in juxtaposition to said turn table, a door normally closing said opening, means for opening said door automatically in the operation of the apparatus, and means for locking said door normally closed and under the control of said carbonated water valve to release the door in the operation of said valve.
35. In automatic liquid dispensing apparatus, a syrup container, a carbonated water container, measuring devices connected to said containers respectively, a discharge pipe connected to said measuring devices, valves controlling communication between said containers and measuring devices and between said measuring devices and pipe and normally in position to cut off communication between said containers and measuring devices and establish communication between said containers and measuring devices and cut off communication between said measuring devices and pipe, means for restoring said valves to normal position whereby the contents of the measuring devices may be delivered to said pipe, means in said carbonated water measuring device movable therein under the action of the incoming carbonated water and operable to discharge the water from said device under pressure in the reverse movement thereof, a turn table below the discharge end of said delivery pipe, cup holders on said turn table movable into line with the discharge end of said pipe successively, means operable from said carbonated water controlled means to rotate said turn table in the filling movement of said carbonated water controlled means immediately preceding the alining of the holders with the pipe, means for dumping said cup holders after each has alined with said pipe to discharge the individual drinking cup therefrom.
36. In automatic liquid dispensing apparatus, a syrup container, a carbonated water container, measuring devices connected to said containers respectively, a discharge pipe connected to said measuring devices, valves controlling communication between said containers and measuring devices and between said measuring devices and pipe and normally in position to cut off communication between said containers and measuring devices and establish communication between said containers and measuring devices and cut off communication between said measuring devices and pipe, means for restoring said valves to normal position whereby the contents of the measuring devices may be delivered to said pipe, means in said carbonated water measuring device movable therein under the action of the incoming carbonated water and operable to discharge the water from said device under pressure in the reverse movement thereof, a turn table below the discharge end of said delivery pipe, cup holders on said turn table movable into line with the discharge end of said pipe successively, means operable from said carbonated water controlled means to rotate said turn table in the filling movement of said carbonated water controlled means immediately preceding the alining of the holders with the pipe, means for dumping said cup holders after each has alined with said pipe to discharge the individual drinking cup therefrom.

uring device movable therein under the action of the incoming carbonated water and operable to discharge the water from said device under pressure in the reverse movement thereof, a turn table below the discharge end of said delivery pipe, cup holders on said turn table movable into line with the discharge end of said pipe successively, means operable from said carbonated water controlled means to rotate said turn table in the filling movement of said carbonated water controlled means whereby a fresh cup holder will be brought into line with said pipe, means for delivering individual drinking cups to said cup holders previous to the latter alining with said pipe, means operable from said carbonated water controlled means to deliver individual drinking cups to said holders in the filling movement of said carbonated water controlled means immediately preceding the alining of the holders with the pipe, means for dumping said cup holders after each has alined with said pipe to discharge the individual drinking cup therefrom, a casing inclosing said apparatus and formed with an opening in juxtaposition to said turn table, a door normally closing said opening, means for opening said door automatically in the operation of the apparatus, and means for locking said door normally closed and under the control of said carbonated water valve to release the door in the operation of said valve.

36. In automatic liquid dispensing apparatus, a syrup container, a carbonated water container, measuring devices connected to said containers respectively, a discharge pipe connected to said measuring devices, valves controlling communication between said containers and measuring devices and between said measuring devices and pipe and normally in position to cut off communication between said containers and measuring devices and establish communication between said containers and measuring devices and cut off communication between said measuring devices and pipe, means for restoring said valves to normal position whereby the contents of the measuring devices may be delivered to said pipe, means in said carbonated water measuring device movable therein under the action of the incoming carbonated water and operable to discharge the water from said device under pressure in the reverse movement thereof, a turn table below the discharge end of said delivery pipe, cup holders on said turn table movable into line with the discharge end of said pipe successively, means operable from said carbonated water controlled means to rotate said turn table in the filling movement of said carbonated water controlled means immediately preceding the alining of the holders with the pipe, means for dumping said cup holders after each has alined with said pipe to discharge the individual drinking cup therefrom.

means whereby a fresh cup holder will be brought into line with said pipe, means for delivering individual drinking cups to said cup holders previous to the latter alining with said pipe, means operable from said carbonated water controlled means to deliver individual drinking cups to said holders in the filling movement of said carbonated water controlled means immediately preceding the alining of the holders with the pipe, means for dumping said cup holders after each has alined with said pipe to discharge the individual drinking cup therefrom, and means for returning said cup holders to normal position in the continued rotation of said turn table.

37. In automatic liquid dispensing apparatus, a syrup container, a carbonated water container, measuring devices connected to said containers respectively, a discharge pipe common to said measuring devices, valves controlling communication between said containers and measuring devices and between said measuring devices and pipe and normally in positions to cut off communication between said containers and measuring devices and establish communication between said measuring devices and pipe, means for operating said valves to establish communication between said containers and measuring devices and cut off communication between said measuring devices and pipe, means for resetting said valves, said carbonated water measuring device embodying a cylinder, a piston in said cylinder capable of movement in one direction under the action of the charged water entering the same, a piston rod connected to said piston and projecting outwardly through one end of the cylinder, a cross head connected to the outer end of said rod, guides for said cross head, a casing inclosing said apparatus and formed with an opening in juxtaposition to said discharge pipe, a door normally closing said opening, connections between said cross head and door for opening the latter in the movement of the cross head under the action of the charged water entering the cylinder, and means locking said door normally in closed position and under the control of said carbonated water valve.

38. In automatic liquid dispensing apparatus, a syrup container, a carbonated water container, measuring devices connected to said containers respectively, a discharge pipe common to said measuring devices, valves controlling communication between said containers and measuring devices and between said measuring devices and pipe and normally in positions to cut off communication between said containers and pipe, means for operating said valves to establish communication between said containers and measuring devices and cut off communication between said measuring devices and pipe, means for resetting said valves, said carbonated water measuring device embodying a cylinder, a piston in said cylinder capable of movement in one direction under the action of the charged water entering the same, a piston rod connected to said piston and projecting outwardly through one end of the cylinder, a cross head connected to the outer end of said rod, guides for said cross head, a casing inclosing said apparatus and formed with an opening in juxtaposition to said discharge pipe, a door normally closing said opening and connections between said cross head and door for opening the latter in the movement of the cross head under the action of the charged water entering the cylinder.

39. In automatic liquid dispensing apparatus, a syrup container, a carbonated water container, measuring devices connected to said containers respectively, a discharge pipe common to said measuring devices, valves controlling communication between said containers and measuring devices and between said measuring devices and pipe and normally in positions to cut off communication between said containers and pipe, means for operating said valves to establish communication between said containers and measuring devices and cut off communication between said measuring devices and pipe, means for resetting said valves, said carbonated water measuring device embodying a cylinder, a piston in said cylinder capable of movement in one direction under the action of the charged water entering the same, a piston rod connected to said piston and projecting outwardly through one end of the cylinder, a cross head connected to the outer end of said rod, guides for said cross head, a casing inclosing said apparatus and formed with an opening in juxtaposition to said discharge pipe, a door normally closing said opening, connections between said cross head and door for opening the latter in the movement of the cross head under the action of the charged water entering the cylinder, a turn table rotatably mounted below said discharge pipe, cup holders mounted upon said turn table and rotatable therewith to move into alinement with said discharge pipe successively in the rotation of the turn table, and means operable from said cross head in the outward movement thereof to rotate said turn table to bring a fresh cup holder into alinement with said pipe.

40. In automatic liquid dispensing apparatus, a syrup container, a carbonated water container, measuring devices connected to

39. In automatic liquid dispensing apparatus, a syrup container, a carbonated water container, measuring devices connected to said containers respectively, a discharge pipe common to said measuring devices, valves controlling communication between said containers and measuring devices and between said measuring devices and pipe and normally in positions to cut off communication between said containers and measuring devices and establish communication between said containers and measuring devices and pipe, means for operating said valves to establish communication between said containers and measuring devices and cut off communication between said containers and measuring devices and pipe, means for resetting said valves, said carbonated water measuring device embodying a cylinder, a piston in said cylinder capable of movement in one direction under the action of the charged water entering the same, a piston rod connected to said piston and projecting outwardly through one end of the cylinder, a cross head connected to the outer end of said rod, guides for said cross head, a casing inclosing said apparatus and formed with an opening in juxtaposition to said discharge pipe, a door normally closing said opening and connections between said cross head and door for opening the latter in the movement of the cross head under the action of the charged water entering the cylinder, a turn table rotatably mounted below said discharge pipe, cup holders mounted upon said turn table and rotatable therewith to move into alinement with said discharge pipe successively in the rotation of the turn table, and means operable from said cross head in the outward movement thereof to rotate said turn table to bring a fresh cup holder into alinement with said pipe.

5 said containers respectively, a discharge pipe common to said measuring devices, valves controlling communication between said containers and measuring devices and between said measuring devices and pipe and normally in positions to cut off communication between said containers and measuring devices and establish communication between said measuring devices and pipe, means for operating said valves to establish communication between said containers and measuring devices and cut off communication between said measuring devices and pipe, means for resetting said 10 valves, said carbonated water measuring device embodying a cylinder, a piston in said cylinder capable of movement in one direction under the action of the charged water entering the same, a piston 15 rod connected to said piston and projecting outwardly through one end of the cylinder, a cross head connected to the outer end of said rod, guides for said cross head, a casing inclosing said apparatus and formed with 20 an opening in juxtaposition to said discharge pipe, a door normally closing said opening, connections between said cross head and door for opening the latter in the movement of the cross head under the action of the 25 charged water entering the cylinder, a turn table rotatably mounted below said discharge pipe, cup holders mounted upon said turn table and rotatable therewith to move into alignment with said discharge pipe successively in the rotation of said turn table, 30 means operable from said cross head in the outward movement thereof to rotate said turn table to bring a fresh cup holder into alignment with said pipe, an individual cup container arranged above said turn table, and means for delivering cups to said holders successively, as the holders 35 approach said pipe.

41. In automatic liquid dispensing apparatus, a syrup container, a carbonated water container, measuring devices connected to said containers respectively, a discharge pipe common to said measuring devices, valves controlling communication between 45 said containers and measuring devices and between said measuring devices and pipe and normally in positions to cut off communication between said containers and measuring devices and establish communication between said measuring devices and pipe, means for operating said valves to establish communication between said containers and measuring devices and cut off communication between said measuring devices and pipe, means for resetting said 50 valves, said carbonated water measuring device embodying a cylinder, a piston in said cylinder capable of movement in one direction under the action of the charged water entering the same, a piston rod con-

connected to said piston and projecting outwardly through one end of the cylinder, a cross head connected to the outer end of said rod, guides for said cross head, a casting inclosing said apparatus and formed 70 with an opening in juxtaposition to said discharge pipe, a door normally closing said opening, connections between said cross head and door for opening the latter in the movement of the cross head under the action of 75 the charged water entering the cylinder, a turn table rotatably mounted below said discharge pipe, cup holders mounted upon said turn table and rotatable therewith to move into alinement with said discharge pipe successively in the rotation of said turn table, means operable from said cross head in the outward movement thereof to rotate said turn table to bring a fresh cup holder into alinement with said pipe, an individual cup 80 container arranged above said turn table, means for delivering cups to said holders successively as the holders approach said pipe, and means operable from said cross head in the outward movement thereof to 85 operate said last-named means.

means under the control of said cup holders and operable therefrom when replaced upon the turn table to release said latching means, and means for closing said door upon the 5 release of said latching means.

43. In automatic liquid dispensing apparatus, a syrup container, a carbonated water container, measuring devices connected to said containers, respectively, a discharge 10 spout connected to said measuring devices, valves controlling communication between said containers and measuring devices and between said measuring devices and spout, and normally in a position to cut off communication between said containers and measuring devices and to establish communication between the measuring devices and spout, and means for operating said valves to establish communication between 15 20 said containers and measuring devices.

44. In automatic liquid dispensing apparatus, a syrup container, a carbonated water container, measuring devices connected to said containers respectively, a discharge 25 pipe connected to said measuring devices, valves controlling communication between said containers and measuring devices and between said measuring devices and pipe, and normally in positions to cut off communication between said containers and measuring devices and establish communication 30 between said measuring devices and pipe, means for operating said valves to establish communication between said containers and measuring devices and cut off communication between said measuring devices and pipe, means for locking said valves in operated position succeeding the release of the operating means thereof, and means under the control of the carbonated water measuring device to unlock said valves succeeding the filling of the carbonated water 35 40 45 50 55 60 measuring device.

pipe, means for operating said valves to establish communication between said containers and measuring devices and cut off 35 communication between said measuring devices and pipe, and means for locking said valves in operated position succeeding the release of the operating means thereof.

45. In automatic liquid dispensing apparatus, a syrup container, a carbonated water container, measuring devices connected to said containers respectively, a discharge pipe connected to said measuring devices, valves controlling communication between 45 said containers and measuring devices and between said measuring devices and pipe, and normally in positions to cut off communication between said containers and measuring devices and establish communication between said measuring devices and pipe, means for operating said valves to establish communication between said containers and measuring devices and cut off communication between said measuring devices and pipe, means for locking said valves in operated position succeeding the release of the operating means thereof, and means under the control of the carbonated water measuring device to unlock said valves succeeding the filling of the carbonated water 50 55 60 measuring device.

In testimony whereof I affix my signature.
BOYD ABERNATHY.
